UNITED STATES PATENT OFFICE.

WILLIAM WALKER, OF AMSTERDAM, NEW YORK, ASSIGNOR TO SHUTTLEWORTH BROS.
CO., OF AMSTERDAM, NEW YORK, A CORPORATION OF NEW YORK.

DESIGN FOR A RUG, CARPET, OR SIMILAR ARTICLE.

51,847.

Specification for Design.

Patented Mar. 5, 1918.

Application filed December 29, 1917. Serial No. 209,590. Term of patent 3½ years.

To all whom it may concern:

Be it known that I, WILLIAM WALKER, a citizen of the United States, residing at Amsterdam, in the county of Montgomery and State of New York, have invented a new, original, and ornamental Design for Rugs, Carpets, or Similar Articles, of which the following is a specification, reference being had to the accompanying drawing, forming part thereof.

The figure of the drawing is a view of so much of a rug, approximately one quarter, as is necessary to show my new design.

I claim:

The ornamental design for a rug, carpet, or similar article, as shown.

WILLIAM WALKER.
